No. 770,737.

PATENTED SEPT. 27, 1904.

A. F. CHASE.

THIRD RAIL FOR ELECTRIC RAILWAYS.

APPLICATION FILED MAR. 17, 1904.

NO MODEL.

UNITED STATES PATENT OFFICE.

ALBERT F. CHASE, OF HADDONFIELD, NEW JERSEY, ASSIGNOR OF ONE-HALF TO STANLEY W. RUSK, OF PHILADELPHIA, PENNSYLVANIA.

THIRD RAIL FOR ELECTRIC RAILWAYS.

SPECIFICATION forming part of Letters Patent No. 770,737, dated September 27, 1904.

Application filed March 17, 1904. Serial No. 198,566. (No model.)

To all whom it may concern:

Be it known that I, ALBERT F. CHASE, a citizen of the United States, residing at Haddonfield, in the State of New Jersey, have invented 5 certain new and useful Improvements in Third Rails for Electric Railways, of which the following is a full, clear, and exact description, reference being had to the accompanying drawings, forming a part of this specification.

10 My invention relates to third-rail conductors for electric railways, and has for its object to provide a third rail of that character which shall be capable not only of performing its primary function as a conductor of 15 propelling current, but shall be provided with superposed flanges and wings integral therewith adapted to operate as a shield to protect the rail conductor, and especially its contact-surface, from all foreign objects, such as accumulations of snow, ice, water, &c.

20 My invention also comprises, in connection with my new rail conductor, an improved hanger to support the rail, a contact-shoe to receive the current from the rail, with a supporting device therefor, the whole constituting 25 a system in which my new form of third rail may be employed to the greatest advantage. These adjunctive elements constituting the system will form the subject of a separate application for Letters Patent, the present invention intended to be described and claimed herein being the improved third-rail conductor now to be described and the distinguishing novel features of which will be pointed 30 out in the claims.

35 In the accompanying drawings, illustrating my said invention, Figure 1 is a transverse vertical section through the rail, and Fig. 2 a diagrammatic view in section illustrating 40 suitable adjunctive devices for supporting the rail and enabling it to perform its intended functions. Fig. 3 illustrates a simple and effective method of producing the depending conductor and its protecting-cover as an integral structure.

45 Referring to Fig. 1 of said drawings, the contact portion of the rail is the depending portion A, and the contact-surface is the under face a thereof. Said depending portion has

its widest part at said under face and of course 50 is constructed thereat of a width proportionate to the face of the contact-shoe E, (see Fig. 2,) intended to receive the propelling current from the rail. The upper part of the depending portion A, which is the rail proper, preferably 55 narrows toward the top into a neck - like form B, terminating in a flat top C, from which spread outward on each side two oppositely-disposed flanges C' C', and from these extend wings d d, which are preferably straight and 60 must incline downward and outward and are of such length as to bring their lower ends in or about the same horizontal plane as the base or contact-face a of the rail proper. Fig. 3 65 illustrates a method by which when the said elements are constructed integral the concrete device may be easily and cheaply rolled. In said Fig. 3 the black lines d d show the inverted base-flange of the rail extended on each side, these flanges being then rolled down into 70 ultimate position to form the wings of the protecting-shed, as shown by the dotted lines in said Fig. 3. In each of the flanges C C' are bolt-holes e e, drilled vertically through the same, to enable my third-rail conductor to be 75 mounted to the rail-hanger F. (See Fig. 2.)

It will be seen that this construction of third rail provides in itself a perfect water-shed over the rail proper and may be made integral therewith, the downwardly-inclined extending wings also protecting the conductor laterally. It is simple in construction for the performance of both its primary and its secondary function and is rolled as one integral structure. It can be insulated without difficulty from the hanger, whether constructed as an integral structure, as in Fig. 1, or in two parts, as in Fig. 2. In Fig. 2 I have shown a preferred means of supporting it and of arranging it relatively to the necessary rail-hanger F and the necessary contact-shoe E and its supporting devices H; but other means may of course be employed for that purpose consistent with so arranging my new third-rail conductor that its rail proper shall be 85 in a depending position with its adjunctive parts constituting the water-shed over and each side of the same.

Having thus described my invention, what I claim as new, and desire to secure by Letters Patent, is—

1. A third-rail conductor, for use in electric third-rail systems, consisting of the combination with a depending contact portion, of a superposed protecting-shed, consisting of a flat portion with oppositely-disposed overhead flanges, and with downwardly-inclined wings proceeding from said flanges.
2. A third-rail conductor having a protecting-shed integral therewith, consisting of a substantially rectangular rail-surface terminating at top in a necked portion with a flat head having laterally-extending flanges proceeding therefrom and with downwardly and

outwardly extending wing-like plates proceeding from the outward ends of the flanges.

3. A third-rail conductor having a protecting-shed integral therewith, consisting of an inverted T-rail having its base-flanges, next to the web portion, prolonged and bent to form downwardly-projecting wings extending coincident with the horizontal plane of the conductor.

In testimony whereof I have hereunto affixed my signature this 27th day of February, A. D. 1904.

ALBERT F. CHASE.

Witnesses:

STANLEY W. RUSK,
H. T. FENTON.
